UNITED STATES PATENT OFFICE.

FRED K. LEWIS, OF ASHTABULA, OHIO.

TOP FOR VEHICLES AND THE LIKE.

1,379,635.

Specification of Letters Patent. Patented May 31, 1921.

Application filed March 29, 1919. Serial No. 236,123.

To all whom it may concern:

Be it known that I, FRED K. LEWIS, a citizen of the United States, and a resident of Ashtabula, county of Ashtabula, and State 5 of Ohio, have invented a new and useful Improvement in Tops for Vehicles and the like, of which the following is a specification, the principle of the invention being herein explained and the best mode in which 10 I have contemplated applying that principle, so as to distinguish it from other inventions.

The present improvements relate more particularly to tops of the so-called "one man" type, such as are now extensively used 15 on automobiles. In this type of top, the extreme forward, or "outrigger bow" as it is called, is carried by means of swinging arms pivotally attached to the main bow at some 20 distance from the point of pivotal attachment of the latter to the vehicle body, so that such arms, with such outrigger bow, extend substantially horizontally in the open position of the top, and together constitute 25 what may be termed an articulated auxiliary bow. To each of these arms, or the rear portions of such articulated auxiliary bow, there is in turn usually attached an intermediate or supplemental bow, the function 30 of which is to support the stretch of cover material between the main bow and the outrigger bow proper.

The object of the present invention is to provide suitable operative connections between the outrigger bow, main bow and such 35 intermediate or supplemental bow, whereby these several bows may be supported in proper relation when the top is in open or extended position, and whereby they will be 40 moved in unison in the folding and unfolding of the top. It is particularly desirable that these connections should not interfere with the compact folding together of the several bows in question; also that the component parts should be as few and light as 45 consistent with strength and rigidity when the top is supported in open position.

To the accomplishment of the foregoing and related ends, the invention, then, consists of the means hereinafter fully described and particularly pointed out in the claims, the annexed drawing and the following description setting forth in detail certain mechanism embodying the invention, such 55 disclosed means constituting, however, but

one of various mechanical forms in which the principle of the invention may be used.

In said annexed drawing:—

Figure 1 is a side elevational view of a top supporting structure embodying my present 60 improvements, such structure being shown as mounted on automobile body or tonneau of conventional form; Fig. 2 is a similar side elevational view of the essential operative parts of a modified form of such top 65 supporting structure; Fig. 3 is a view similar to Fig. 2, but showing still another modification in construction; and Fig. 4 illustrates the same construction as does Fig. 3, but with the structure in partially 70 folded condition.

It is of course a matter of indifference whether the top is used on automobile, motor-boat or otherwise, and, depending upon its longitudinal extent, a smaller or larger 75 number of bows, in addition to the outrigger structure of present interest, may be utilized. It will also be understood that the term "bow" is used herein inclusively to designate not merely the wooden bow 80 proper, but also the metallic sockets carrying the same, these parts when regarded in side elevation constituting the equivalent of the so-called "sticks," as they are called, in the old wood structure. It is accordingly a 85 matter of convenience to refer to the parts in the singular, as though the structure all lay in a single vertical plane, since the parts do actually lie in such a plane.

Referring, first of all, to the construction 90 illustrated in Fig. 1, the top covering 1 is designed to be entirely supported through an appropriate outrigger from a single main bow 2. The latter, which is of substantial construction, in view of the weight it is thus 95 designed to carry, is pivotally supported upon or attached to the body at the point 3 in the usual manner, so that it may be laid down and carried in a substantially horizontal plane when the top is not in use. 100 Normally, in the extended or open condition of the top, said main bow 2 inclines rearwardly at an angle of approximately forty-five degrees to the horizontal, being held from rising higher by the top covering 105 or rather by special straps (not shown), or extensions of the longitudinal strainers, which, as is well known, are used to connect the bows together and provide supporting means for the top covering intermediately 110

between said bows. For the purpose in hand such straps or strainers may be regarded as a part of the covering material.

The outrigger structure comprises a main 5 articulated auxiliary bow, or, as it is sometimes called, outrigger bow 6, the latter term referring more particularly to the outer portion or bow 7 proper, which is secured to the main bow 2 by means of an arm 8 (one on 10 each side of course) pivotally attached to said main bow and to the rear end of such outrigger bow, and so constituting the inner portion of said articulated auxiliary bow 6. The point of attachment of this arm to the 15 main bow is preferably in line with, or just above, the side edge of the cover, so as to be hidden by the latter, and the joint 9 between said arm and the outrigger bow is a rule or lock joint disposed so as to prevent further bending of the arm in question, when extended in horizontal fashion, as in open condition of the top illustrated in Fig. 1.

Pivots attached to the arm 8 is a supplemental bow 10 whose angular position in 20 the open condition of the top is so adjusted, by means presently to be described, as to support the top covering at a suitable point intermediate between main bow 2 and outrigger bow 7. For the purpose of operatively connecting this supplemental bow 30 with said main and outrigger bows, I employ a three-part articulated link or brace, the longer part 11 thereof being pivotally attached at its forward end to the outrigger bow at a point slightly in advance of the 35 joint 9 therein, while said link-part is similarly pivotally attached near its rear end to the supplemental bow adjacent the point of pivotal attachment of the latter to the swinging side arm 8. In the form of construction under consideration said link-part 11 projects beyond its point of attachment to said supplemental bow, the other parts 12 and 13 connecting such extension with the main 40 bow 2, or rather with a bracket 14 thereon, which at the same time provides the pivot for attachment of the swinging side arm 8 to said bow. The intermediate link-part 12 is relatively short compared with both the 45 other link parts, and functions in a sense as an equalizer member, rendering the connection between the supplemental bow and the main bow a flexible one, and so permitting such supplemental bow a range of movement 50 that would not be possible if only two link-parts were employed, or if, as has been attempted, a single long link or brace were utilized to connect the three bows in question together.

60 By virtue of the construction just described, the same degree of rigidity is obtained in the top structure when extended as though a single rigid brace were utilized, but when the top is being folded (or opened) 65 any tendency to bind, owing to lack of ac-

curate correlation in the swinging movement of the various parts, is avoided through the flexible character of the connection provided. This flexibility is of equal importance in the setting up of the top during the course of manufacture, since it allows a certain latitude in the location of the intermediate bow.

In the modified construction illustrated in Fig. 2 the arrangement of bows is identical with that illustrated in Fig. 1, and just described above, the only difference consisting in the arrangement of the parts of the articulated link or brace. The forward member 11^a does not have in this case a rearwardly projecting extension beyond the 75 point of its pivotal attachment to the intermediate bow 10, but the intermediate or equalizer link 12^a is connected with said part 11^a forwardly of its point of attachment with said intermediate bow. The remaining part 80 13^a which is attached to the bracket 14 is, to all intents and purposes, the same as the part 13 in the first described construction. It will be noted that the rear end of link-part 11^a is dropped, i. e. curves downwardly 90 so as to allow the point of pivotal connection of the intermediate link 12^a to clear the point of connection of said part 11^a with the intermediate bow. The mode of operation of this form of the invention is the same as that 95 already described.

In the remaining construction, that illustrated in Figs. 3 and 4, the arrangement of main, outrigger and intermediate bows, is again the same as that described in connection with the form shown in Fig. 1, and the three-part articulated link or brace is likewise very similar, the difference lying primarily in the use of a lock joint 15 between the rear link-part 13^b and intermediate 100 or equalizer part 12^b, whereby an increased degree of rigidity is obtained in the extended or open position of the top structure. Also the rear extension 16 of the forward link-part 11^b curves upwardly slightly, and in the 105 extended position of the parts, said intermediate link 12^b inclines downwardly in a reverse direction therefrom, as clearly shown in Fig. 3. The manner in which the parts in this particular construction fold together, 110 is well illustrated in Fig. 4, which shows the top structure in its partially folded position, i. e. with the outrigger and intermediate bows brought into parallel relation with the 115 main bow.

In all three modifications of the structure it is desirable to provide a stop 17 on the swinging side arm 8 which engages with the intermediate bow 10 so as to determine its position when the top is open or extended. 125 The action of this stop, in the case of the construction shown in Fig. 3, is of course supplemental to that of the top joint 15 between link-parts 12^b and 13^b.

The improved top supporting structure is 130

particularly adapted for use on roadster and close-coupled types of automobile bodies, but by proper proportioning of the length of bows employed, may be utilized on touring car bodies as well.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

15 1. In a top for vehicles and the like, the combination of a main bow; a two-part articulated auxiliary bow having its rear portion pivotally connected to said main bow; a supplemental bow pivotally connected to such rear portion of said auxiliary bow; a link pivotally attached to said supplemental bow and to said auxiliary bow beyond the joint therein; and a flexible member connecting said link with said main bow.

20 2. In a top for vehicles and the like, the combination of a main bow; a two-part articulated auxiliary bow having its rear portion pivotally connected to said main bow; a supplemental bow pivotally connected to such rear portion of said auxiliary bow; a link pivotally attached to said supplemental bow and to said auxiliary bow beyond the joint therein; and a flexible member consisting of plural interconnected links connecting said first link with said main bow.

25 3. In a top for vehicles and the like, the combination of a main bow; a two-part articulated auxiliary bow having its rear portion pivotally connected to said main bow; a supplemental bow pivotally connected to such rear portion of said auxiliary bow; a link pivotally attached to said supplemental bow and to said auxiliary bow beyond the joint therein; and a flexible member consisting of plural interconnected links connecting said first link with said main bow.

30 35 3. In a top for vehicles and the like, the combination of a main bow; a two-part articulated auxiliary bow having its rear portion pivotally connected to said main bow; a supplemental bow pivotally connected to such rear portion of said auxiliary bow; a link pivotally attached to said supplemental bow and to said auxiliary bow beyond the joint therein; and a flexible member consisting of plural interconnected links connecting said first link with said main bow.

40 45 4. In a top for vehicles and the like, the combination of a main bow; a two-part articulated auxiliary bow having its rear portion pivotally connected to said main bow; a supplemental bow pivotally connected to such rear portion of said auxiliary bow; a link pivotally attached to said supplemental bow and to said auxiliary bow beyond the joint therein; and two other links pivotally connected together the one thereof being pivotally attached to said first link and the other being similarly attached to said main bow.

50 55 5. In a top for vehicles and the like, the combination of a main bow; a two-part articulated auxiliary bow having its rear portion pivotally connected to said main bow; a supplemental bow pivotally connected to such rear portion of said auxiliary bow; a link pivotally attached to said supplemental bow and to said auxiliary bow beyond the joint therein; and two other links, one relatively short, pivotally connected together, said short link being pivotally attached to said first link and the long one to said main bow.

60 65 6. In a top for vehicles and the like, the combination of a main bow; a two-part articulated auxiliary bow having its rear portion pivotally connected to said main bow; a supplemental bow pivotally connected to such rear portion of said auxiliary bow; a link pivotally attached to said supplemental bow and to said auxiliary bow beyond the joint therein; and two other links pivotally connected together by a joint adapted to lock in the extended position of the parts, said links being respectively pivotally attached to said first link and said main bow.

Signed by me, 26th day of March, 1919.
FRED K. LEWIS.
